UNITED STATES PATENT OFFICE

CHESTER D. MORALES, OF RAYMOND, WASHINGTON

HEEL PROTECTOR FOR HOSE

Application filed June 3, 1931. Serial No. 541,873.

The object of the invention is to provide a device for protecting the heel of hose, and more particularly to provide a device adapted to be worn in the heel portion of the shoe 5 for protecting the heel of golf stockings.

A still further object of the invention is to provide a protector of the above mentioned character, which can be readily inserted in the heel of the shoe, which is inexpensive, 10 will aid in increasing the life of the golf stocking, and which will be neat and attractive in appearance.

Other objects and advantages of the invention will become apparent from a study 15 of the following description, taken in connection with the accompanying drawings wherein:

Figure 1 is a side elevational view of a heel portion of a shoe having my protector 20 applied thereto.

Figure 2 is a plan view of the protector.

Figure 3 is a sectional view taken substantially on the line 3—3 of Figure 2.

Figure 4 is a plan view of the blank from 25 which the protector is formed.

With reference more in detail to the drawings, it will be seen that my improved heel protector is cut or formed from a single blank of material 5 suitably cut and shaped 30 to provide a plate like pad portion 6 having side portions 7 rising from opposite edges thereof and connected at the rear of the pad by a curved portion 8. The sides 7 and rear end portion 8 at their upper edges are fold- 35 able on an imaginary line continuing from one to the other of the edges 5a of the blank 5 to provide a cuff 9 adapted to receive between it and the sides 7 and rear 8 corresponding portions of the shoe counter at the 40 heel of the shoe for retaining the protector in position at the heel portion of the shoe. At the edges 5a of the blank, which edges prevent the forward edges of the sides 7, the 45 foldable or cuff portions 9 is separated from the side forming portions 7 by relatively

short slits 9' extending inwardly from the edges 5a so that when the protector is properly positioned within the heel of the shoe and the cuff 9 is folded over the outer face of the shoe counter there will be no upward pull 60 on the side forming portions 7 with the result that the bottom forming member 6 will rest properly on the bottom of the shoe and the side forming members 7 will rest in flat contact with the corresponding portions of the 65 counter.

From a study of Figure 4 it will be also noted that the side forming portions 7 at their lower edges, that is at the edges 7a of the blank 5 are separated from the bottom 60 forming member 6 by slits 7' extending inwardly from the said edges 7a so that the lower portion of the sides 7 will be free to conform to the curvature of the counter as it approaches the bottom of the shoe heel. 65

The part 6 of the blank 5 provides a top covering for a layer of felt 10, 10 and 6 thus providing a soft comfortable pad upon which the heel of the foot rests when the protector is inserted in the heel portion of the shoe. 70 Preferably, the material forming the blank 5 is of leather or soft kid while the turned down or cuff forming portion 9 may be suitably treated so as to render said portion sufficiently stiff as to function suitably for retaining the protector in position within the heel of the shoe. 75

In actual practice, the device is placed in the heel portion of a conventional type of "half shoe S" with the pad 10 forming a 80 cushion upon which the heel of the foot rests and the sides 7 extend along opposite side portions of the shoe counter and the curved end portion conforms to the back of the shoe heel, the upper edge of the shoe counter being overlapped by the cuff or turn down portion 9.

When the protector is so positioned in the shoe it will be apparent that the heel portion of the stocking as for example the golf stock- 90

ing will be protected against direct contact with the counter of the shoe and will thus prevent wearing of the heel of the hose not only at the back of the heel but also at the 5 sides of the heel.

To add to the comfort of the device, the pad 10 at its forward end is reduced in thickness or beveled as at 11 at a point of the pad which will be under the oscalcis bone of the heel 10 preventing the foot from pulling away from the heel of the shoe which results in extra wear at the point of contact of the hose. Of course, the forward edge of the pad 10 and cover portion 6 of the blank 5 will be suit- 15 ably shaped dependent upon whether the pad is to be used with the right or left shoe, that is to say, the bottom forming member 6 at its forward end is reduced in width as it proceeds to said forward end from a point inwardly from said end and a side edge of the bottom forming portion 6 as it proceeds from the wide portion of the bottom 6 to the extremely of the reduced end thereof is concave as at 6a. The beveled portion 11 of the pad 20 10 at its forward end is also shaped to conform to the shape of the forward portion of the bottom 6 as is thought apparent.

Even though I have herein shown and de- 25 scribed the preferred embodiment of the in- vention, it is to be understood that the same is susceptible to changes, modifications and improvements coming within the scope of the appended claims.

Having thus described my invention, what 30 I claim as new is:

1. As a new article of manufacture, a shoe attachment comprising a single blank of material presenting a bottom portion, opposed side portions, and a transversely curved end portion connecting the rear ends of the side portions; the upper marginal edges of the side and end portions being foldable on an imaginary line continuing from the forward end of one side portion to the corresponding 40 end of the other side portion; the foldable marginal portion at opposite edges of the blank being separated from the side portions by short longitudinal slits extending inwardly from the said edges of the blank; and the side portions at the bottom edges thereof being separated from the bottom portions by relatively short slits extending inwardly from the edges of the blank constituting a said lower edge portion of said sides.
2. As a new article of manufacture a pro- 50 tector for the heel of hose and comprising a single blank of flexible material substantially T-shaped in plan and providing relatively wide side and end forming portions and a relatively narrow bottom forming portion, the latter having opposite longitudinal edges laterally separated from the wide portion of the blank by relatively short slits extending inwardly from the proximate edges of the 55 said wide side and end forming portions, the

said side and end forming portions of the blank having relatively short slits extending inwardly from opposite lateral edges of the blank; and also having a marginal cuff forming portion foldable on an imaginary line 70 extending between the slits and in line therewith; the said side and end forming portions being also foldable on an imaginary arcuate fold line connecting the inner ends of the first named slits, said wide portion being also foldable on imaginary lines continuing inwardly from the said inner ends of the said second named slits and transversing the cuff forming portion.

In testimony whereof I affix my signature. 80
CHESTER D. MORALES.
